CABINET AIR-MIXER FOR INSTALLATION
AGAINST WALLS

John M. Redmond, Jr., Wichita, Kans., assignor
to The Coleman Company, Inc., Wichita, Kans.,
a corporation of Kansas

Application November 27, 1950, Serial No. 197,713

7 Claims. (Cl. 98—38)

1

This invention relates to a cabinet air-mixer for installation against a wall. The invention is particularly useful in connection with a cabinet in which heated air is mixed with room air and the mixed air then discharged into the room, the cabinet being installed so as to fit tightly against a room wall.

An effective means for heating a room is by discharging into a cabinet having a spaced inlet and outlet highly heated air so as to induce room air within the cabinet for admixture with the heated air and then discharging the mixture into a room. Such a system is shown in considerable detail in the co-pending application of Jack W. Kice, Serial No. 760,572, filed July 12, 1947, now abandoned. Considerable difficulty has been experienced in the employment of an air-mixer cabinet so as to make the same fit tightly against a wall and thus to avoid streaking the wall, while at the same time avoiding the overheating of the wall. The ordinary wall surfaces of a room are found to be highly irregular, and when the back plate of the cabinet is placed against the wall, there are wide spaces and channels formed through which foreign material is from time to time ejected, causing a streaking of the wall. Such movement of foreign material is usually induced by the heat radiated from the back plate, and such heat, in addition to causing the unsightly results described, also have an adverse effect upon the wallpaper or plaster wall of the room itself. There has long been a need for a cabinet which might be effectively anchored against the wall to prevent such streaking while at the same time insulating the cabinet from the wall.

An object of the present invention is to overcome the above difficulties and to provide a cabinet which avoids undue heating of the wall while at the same time providing a tight seal between the cabinet and the wall to avoid the above mentioned discoloration or streaking of the wall. A further object is to provide a cabinet structure having flanged portions spacing the main cabinet from the wall and presenting edges which provide a close contact with the wall surface in spite of irregularities therein, while also providing a flanged portion which may be cut away to receive the baseboard of the wall. A still further object is to provide a structure having means for anchoring it securely against the wall while providing a cabinet chamber spaced forwardly of the wall and provided with spaced inlet and outlet openings. Other specific objects and advantages will appear as the specification proceeds.

2

The invention is shown in an illustrative embodiment by the accompanying drawing, in which—

Figure 1 is a perspective view of a cabinet structure embodying my invention; Fig. 2, a side view in elevation; Fig. 3, a view similar to Fig. 2 but showing a side flanged portion cut away to receive the baseboard of a room; Fig. 4, a broken view taken from the inside of the cabinet and showing the flanged side portion which is to be cut away to receive the baseboard; and Fig. 5, a perspective view of the wall bracket which may be employed.

In the illustration given, I provide a shell member 10 which extends downwardly at an inclination and is provided at its top with a rearwardly extending top wall 11. The shell is provided with rearwardly extending side walls 12. Within the chamber thus provided by the shell 10, I secure an imperforate casing wall 13, which is united to the side walls 12 and which is directed forwardly at 14 to provide a top wall for the inner chamber. The imperforate wall 13, together with the side walls extending forwardly thereof, the top wall 14, and the forward portion of the panel 10, provide thus a chamber 15 which is effective as an air-mixer chamber. The front panel of casing 10 is provided at its upper side with a vane-equipped outlet 16, and at its bottom with a vane-equipped inlet 17. A pipe 18 of reduced cross section leads from a furnace or other source of hot air and terminates at a point above the inlet 17 and within the chamber 15. Thus, when hot air is discharged at high velocity through pipe 18, air is drawn from the room through inlet 17 into the chamber 15 and the mixture of heated air and room air is then passed out of the outlet opening 16 at the upper end of the shell.

By the structure above provided, the air-mixing cabinet actually comprises the structure forwardly of the wall 13 and the portions of the side wall 12 extending rearwardly of wall 15 actually from side extensions 19 beyond the actual air-mixer cabinet. Similarly, the rear portion of the top wall 11, which extends rearwardly of wall 13, provides in effect an extension 20 of the top wall. Such extended portions of the top wall and side walls of the cabinet serve to space the real cabinet structure forwardly of the wall and thus to provide an insulation space between it and the room wall.

In the illustration given, the room wall is designated by the numeral 21, and it is shown provided with a baseboard 22. It is a known fact that the baseboards of rooms vary greatly in

depth, height, and in specific conformation. For that reason, it is impossible to provide a cabinet with a shape which will exactly fit the conformation of any and all baseboards. In the structure shown, I find that the side wall extension portion 19, which is preferably formed of sheet metal, may be cut readily by the person making the installation so as to make the cut-out portion indicated by the line 23 in Fig. 3, and by dotted lines in Fig. 4, fit the particular baseboard 22 to which it is to be applied. Thus the extended side walls 19 serve two important functions. They provide flange portions which may readily be cut away to receive the conformation of the baseboard, while also presenting narrow edges which form a tight seal with the room wall in spite of irregularities therein. Further, such flanges or side wall extensions space the actual back wall of the cabinet (wall 13) from the room wall and provide an insulating space therebetween.

It will be observed that the cutting away of the side wall portion near the bottom along line 23 does not in any way injure the rear wall 13 of the cabinet, and the cabinet thus remains intact as a means for providing an air-mixing chamber.

I have found that the cabinet can be supported firmly and securely against the wall by employing bracket means which will now be described.

To the side wall I secure a bracket member 25 having apertures 26 through which screws or other means may be passed into the wall for securing the bracket in position. The bracket 25 is provided at its ends with spring flanges 27 having slots 28 therein. With the bracket located as shown, the spring flanges 27 will bear against the side walls 19 of the cabinet and a screw 29 on each side of the cabinet may be passed through the wall portion 19 to engage the slot 28 in each flange 27. By this means, the upper end of the cabinet is securely anchored in position.

To anchor the bottom portion of the cabinet, I prefer to secure to the floor below the cabinet a bracket strip 30. The strip 30 is provided with openings 31 for receiving screws or other fastening means and is preferably provided with upturned end flanges 32 which are adapted to bear against the inner surface of the cabinet wall 12. The flange 32 may be provided with an aperture 33 for receiving a screw which passes through a similar opening 34 in the lower end of the cabinet 12.

The bracket 30 is also utilized for receiving and supporting the hot air pipe 18. Thus the bracket 30 and pipe 18 provide an assembly which may be installed simultaneously for anchoring the lower portion of the cabinet and simultaneously supporting the air pipe 18 centrally within the cabinet.

While in the foregoing specification, I have set forth a specific structure in considerable detail for the purpose of illustrating one embodiment of the invention, it will be understood that such details may be varied widely by those skilled in the art without departing from the spirit of my invention.

I claim:

1. An air-mixer cabinet adapted to be installed against a room wall provided with a baseboard, comprising a shell forming an air-mixing chamber provided with an air inlet spaced from an air outlet, said shell having its top wall and side walls extended rearwardly to abut throughout substantially the entire lengths thereof against the room wall at a distance from the rear wall of

said chamber, said side walls being of thin metal and being cut away to fit the conformation of said baseboard and abut thereagainst when the rear edges of said side walls and top wall are pressed against said room wall, whereby a substantially dead air space is provided between said room wall and said air-mixing chamber with the result that the air between said cabinet and wall does not move upwardly from said cabinet when heated.

2. An air-mixer cabinet adapted to be installed against a room wall, comprising a shell having front, rear, top and side walls providing an air-mixing chamber, the front wall thereof being provided with an air inlet and an air outlet spaced from the inlet, the side walls and top walls of said shell being extended rearwardly to abut throughout substantially the entire lengths thereof of the room wall at a distance rearwardly of said shell rear wall to provide a substantially dead air space between said room wall and shell rear wall, and a bracket adapted to be secured to the room wall and provided with end spring flanges adapted to engage the inner end walls of said cabinet, said flanges being provided with openings for receiving screws passing through the side walls of said cabinet.

3. An air-mixer cabinet adapted to be installed against a room wall, comprising a shell having front, rear, top and side walls providing an air-mixing chamber, the front wall thereof being provided with an air inlet and an air outlet spaced from the inlet, the side walls and top walls of said shell being extended rearwardly to tightly abut the room wall at a distance rearwardly of said shell rear wall to provide a substantially dead air space between said room wall and shell rear wall, and a bracket adapted to be secured to the floor and provided with end flanges adapted to slideably engage the inner side walls of said cabinet, said bracket being apertured to receive a hot air pipe extending upwardly into said cabinet.

4. An air-mixer cabinet adapted to be installed against a room wall, comprising a shell forming an air-mixing chamber provided with an air inlet spaced from an air outlet, said shell having its top and side walls extended rearwardly to abut the room wall at a spaced distance from the rear of said chamber to provide a closed insulating space between the room wall and rear wall of said chamber, a bracket adapted to be secured to the room wall and provided with end spring flanges engageable with the inner side wall surfaces of said cabinet, a floor bracket having spring end flanges engageable with the inner surfaces of the side walls of said cabinet, and a hot air pipe extending through and carried by said floor bracket.

5. An air mixer cabinet adapted to be installed against a room wall, comprising a shell forming an air mixing chamber provided with an air inlet and an air outlet spaced therefrom, said shell having its top wall and side walls extended rearwardly to abut throughout substantially the entire lengths thereof the room wall at a spaced distance rearwardly of said chamber, and a bracket adapted to be secured to the room wall and provided with end spring flanges adapted to engage the rearwardly-extended side walls of said cabinet, said flanges being provided with openings for receiving screws passing through the rearwardly-extending side walls of said cabinet.

6. An air mixer cabinet adapted to be installed against a room wall provided with a baseboard,

comprising a shell forming an air mixing chamber provided with an air inlet and spaced therefrom an air outlet, said shell having its top wall and side walls extended rearwardly to about throughout substantially the entire lengths thereof of the room wall at a distance from the rear wall of said chamber, said side walls being arranged to conform to the configuration of said baseboard and abut thereagainst when the rear edges of said side walls and top wall are pressed against said room wall, whereby a substantially dead air space is provided between said room wall and said air mixing chamber with the result that the air between said chamber and room wall does not move upwardly from said cabinet when heated.

7. The structure of claim 6 in which a hot air pipe extends upwardly and into said chamber

and terminates adjacent said inlet, said hot air pipe extending through a bracket secured to the side walls of said cabinet and being adapted to be secured to the floor of a room space.
